Specification for Design.

Patented Apr. 5, 1921.

Application filed May 31, 1916. Serial No. 100,974. Term of patent 3½ years.

To all whom it may concern:

Be it known that I, JOHN JANUCHOWSKY, a citizen of the United States, residing at St. Louis and State of Missouri, have invented a new, original, and ornamental Design for a Handhole-Cover for Boxes, of which the following is a specification, reference being had to the accompanying drawing, forming part thereof.

Figure 1 is a perspective view of the outside of this improved hand hole cover.

Fig. 2 is a perspective view showing the opposite side of Fig. 1.

This invention relates to the production of a new and original Design for a hand hole cover or similar article as relating to cases or boxes that are adapted to be hand gripped.

I claim:

The ornamental design for a hand hole cover for boxes, as shown.

JOHN JANUCHOWSKY.
